UNITED STATES PATENT OFFICE.

CARLO DE FELICE, OF NEW YORK, N. Y.

GUN-LOADING MECHANISM.

1,304,274.

Specification of Letters Patent.

Patented May 20, 1919.

Refile for (abandoned) application filed November 23, 1917, Serial No. 733,121. Application filed December 5, 1917. Serial No. 205,515.

To all whom it may concern:

Be it known that I, CARLO DE-FELICE, a citizen of the United States, residing in the borough of Manhattan, in the city, county, and State of New York, have invented certain new and useful Improvements in Gun-Loading Mechanisms, of which the following is a full, clear, and exact description, reference being had to the accompanying drawings, forming a part of the specification.

This application is a refile for abandoned application Serial No. 733,121 filed November 23rd, 1912, allowed October 6, 1915.

This invention relates to improvements in firearms or rifles and particularly to automatic firearms in which the recoil is utilized for expelling the used shell and for recharging the arm.

The principal object of this invention is to provide an improved arrangement of rotatable cartridge magazine and devices for the delivery of cartridges from the same to the firing chamber, said devices being operated by the recoil of the gun.

A further object is to provide an improved mechanism operated by the recoil of the gun, for rotating the magazine as each shot is fired in order to bring a new storage chamber of the said magazine in correspondence with the gun firing chamber.

A still further object is to provide an arrangement of a simple construction for efficiently and automatically delivering cartridges to the firing chamber of a gun from a magazine mounted in the stock of said gun and capable of holding a great quantity of cartridges in a number of longitudinal storage chambers provided in the same.

With these and other objects in view, this invention comprises certain novel constructions and arrangements of parts as will be hereinafter fully described and set forth in the appended claims.

In the accompanying drawings, Figure 1 is a side view in elevation illustrating the general appearance of my improved gun; Fig. 2 is a detail side view in elevation partly broken away, illustrating in detail the connection between the magazine and the firing chamber; Fig. 3 is a detail plan view of a portion of the surface of the rotating magazine; Fig. 4 is a detail sectional view in elevation illustrating the interior of a storage chamber of the magazine; Fig. 5 is

a detail side view in elevation of my gun partly broken away, illustrating the operating connections between the recoil operated plunger and the magazine revolving mechanism; Fig. 6 is a detail side view in elevation of the firing mechanism; Fig. 7 is a detail side view in elevation of my improved magazine, partly broken away to show the interior; Fig. 8 is a detail sectional view in elevation illustrating the outlet tube, conveying the cartridges from said magazine to the gun barrel; Fig. 9 is a front view in elevation of said outlet tube; Fig. 10 is a front view in elevation of the magazine revolving mechanism; Fig. 11 is a detail side view in elevation of the device for transmitting the motion to the rotating magazine; Fig. 12 is a rear view in elevation partly broken away of said magazine; Fig. 13 is a detail side view in elevation of the device for feeding the cartridges to the gun barrel; Fig. 14 is a rear sectional view in elevation through line A—A of Fig. 13; Fig. 15 is a detail side view in elevation of the sides of the casing within which said feeding devices are located; Fig. 16 is a sectional front view in elevation of the same; and Fig. 17 is a detail view in perspective illustrating the rear part of the breech block.

The utilization of the force of recoil in devices of this kind for expelling the empty cartridges and for recharging the gun, is, broadly speaking, old and has been applied in many different ways. The force of recoil has also been utilized in connection with rotatable magazines for rotating the same as each shot is fired, but arrangements of this kind have been devised only in connection with magazines capable of holding a limited number of cartridges, a single cartridge being generally held in each storage chamber provided in the magazine.

In the present device I have sought to combine the advantages deriving from the utilization of the pressure of the gases in the bore and those deriving from a rotatable magazine capable of holding a considerable number of cartridges for producing a gun of a simple construction capable of firing a great number of shots in quick succession.

Referring to the drawings in which I illustrate my arrangement as applied to a rifle, 20 is the stock of the rifle in which is mounted a hollow magazine chamber 21;

- 22 is the gun barrel, 23 is the firing mechanism; in Fig. 2, 24 is the breech block provided with a firing pin 25, operated by a hammer 26, shown in its cocked position.
- 5 Upon pressing trigger 27 with the finger, the detent is operated in any convenient manner and hammer 26 will strike firing pin 25, provoking the explosion of the shell 28 in the firing chamber. Breech block 24
- 10 is provided with a rod 29 projecting toward the front part of the gun, said rod compressing a spring (not shown) inclosed within the front part 30 of the stock when said breech block is moved backward, as is usual in
- 15 automatic recoil operated guns. Said rod 29 can be used for moving the breech block by hand and therefore also for operating the magazine revolving mechanism connected to it as will be hereinafter described.
- 20 At one side of breech block 24 is provided a pin 31 inserted through a slot 32 of a rack 33. Said rack is mounted at one side of the box containing the firing mechanism and is in mesh within a pinion 34, which in
- 25 its operation is in mesh with another rack 35 which will thus move in an opposite direction to rack 33; therefore when one shot is fired and the breech block is pushed backward by the force of the recoil, rack 35 will
- 30 be moved forward.
- The firing mechanism is provided with a tube 36 loading the cartridges coming from the magazine to the firing chamber. Magazine chamber 21 has a circular section as
- 35 shown in Fig. 12 and is provided in its upper part with two plates 37 between which is guided ejector 38; said ejector is provided with a number of equi-distant prongs or teeth 39 the distance between two successive
- 40 prongs being efficient to accommodate the length of a cartridge. The same is also provided with a projection 40 on which is inserted a tube 42 connected at the opposite end to a part 43 provided with a cam-slot 44.
- 45 Said magazine chamber is provided at its forward end with a wall 45, provided with an opening 46 at the upper part of a diameter sufficient for the passage of the outlet tube for the cartridges. At the rear
- 50 end of said magazine chamber is provided a bottom 47, and within said magazine chamber is revolvably mounted a magazine drum 48, fixed on a shaft 49. Said shaft 49 projects through and out of the wall 45, and
- 55 on its outer projection is fixed a wheel 50, having a ratchet 51 and a cam-portion 52 provided with a number of cam-slots 53, circumferentially arranged on the outer face of said part 50.
- 60 Said magazine drum is formed with a number of longitudinal cartridge storage chambers 54, arranged along its periphery; said chambers being of a diameter sufficient to accommodate the cartridges used and
- 65 communicating with the outside face of the

drum by means of longitudinal slots 55. The upper storage chamber 54 is normally registering with opening 46 in wall 45 and through its related slot 55, ejector 38 is inserted and operating.

70 The length of the magazine is such that each storage chamber can accommodate a number of cartridges end to end, as illustrated in Figs. 3 and 4; each storage chamber is provided with a number of springs 56, 75 allowing the motion of the cartridges forward but preventing their motion in the opposite direction.

Communication between tube 36 and the upper storage chamber is established by 80 means of an outlet tube 57, inserted through the front end 58 of the magazine chamber and through opening 46, said outlet tube extends into the rear end of tube 36, which is connected to part 58 by means of dowel pins 59, 60 or in any other convenient manner. Said outlet tube 57 is also provided, as shown, with a spring 61, permitting the motion of the cartridges forward, but preventing free motion in the opposite direction.

85 Rod 41 is connected to tube 42 by means of a tension spring 62, located within said tube; and rack 35 is connected to part 43 in any suitable manner, for instance, by inserting 95 its bent rear end in a housing 63, formed in said part 43. As each shot is fired, magazine 48 is rotated one step, said movement being controlled by a lever 64, pivoted in 65 to a connection 66; said lever is provided with a pin 67, adapted to project within cam-slots 53 and to operate against the sides of the same. Spring 69 will cause lever 64 to swing outwardly, that is to the right looking at the drawing, Fig. 10, when pin 67 is disengaged from cam-slots 53. This disengagement of pin 67 takes place when connection 66 is moved toward shaft 49. Upon said inward radial motion of connection 66 taking place, pin 67 comes out of the cam slot 53 into which the same was previously projecting, spring 69 will cause lever 64 to swing outwardly, and pin 67 will then be ready to engage the next cam slot 53 to right. The downward motion of connection 66 takes place when part 43 is moved forward, and when said part 43 returns to its normal position through the action of the spring within part 30 which controls the motion of rack 35, connection 66 will be moved outwardly and will cause magazine 48 to rotate one step, as will be hereinafter explained.

100 By observing the shape of cam-slots 53, it can be seen that while the right side of the 105 same is in a radial direction, the left side is inclined in such a manner that a pressure exerted against its surface by a part moving in a radial direction will rotate the cylinder toward the left. Connection 66 is provided 110

with a vertical elongated slot 70, accommodating shaft 49 and permitting the up and down motion of said connection 66. The upper part 71 of said connection projects above front part 58 and is bent to one side to clear outlet tube 57; said upper part 70 is provided with a pin 72 projecting through slot 44 of part 43, and which in the position of rest occupies the highest point of said slot, as illustrated in Figs. 2, 5, and 7.

As above explained, when a shot is fired, the recoil pushes back breech block 24, and thus through rack 33 and pinion 34, causes the forward motion of rack 35, this being connected to part 43 it will pull the same forward, therefore slot 44, which is inclined downward will cause the downward motion of connection 66, freeing projection 67 from the cam slot 53 to which the same was engaged. As soon as said cam slot 53 has been entirely cleared by pin 67, spring 69 will swing lever 64 outward and therefore pin 67 will be ready to engage the next cam slot 53. The upward motion of lever 64 is limited by a roller 64', abutting against its side, which will cause the same to assume its normal position when connection 66 will again move outward.

As soon as the empty shell of the cartridge which has been fired has moved back sufficiently to clear the firing chamber and to be expelled at one side in any convenient manner, a new cartridge can be inserted in said firing chamber from the forward end of tube 36. To insure the unloading and reloading of the gun in a proper manner, the different parts constituting the firing mechanism are formed and related in a special way. The forward end of tube 36 is cut in an inclined direction in relation to its axis, so as to remain parallel to the motion of the breech block and abutting against the same. At the upper part of said tube 36 is provided a catch 73 pivoted in 74, and a spring 74 tends to hold the same away from inside of tube 36.

When hammer 26 is in its forward position, however, it will force said catch 73 down; the backward motion of breech block 24 forcing back hammer 26, will temporarily free said catch, permitting the same to move clear of the inside of tube 36, said breech block being grooved at 73' to allow the outward motion of said catch; after a certain portion of the backward stroke of said breech however, when groove B' ends said catch will again be forced down through the action of the inclined surface 73'' at the end of groove 73'. When said catch is forced down it will abut against the cylindrical portion of the cartridge underneath, and will prevent the forward motion of the same, because the rear part of the shell having an enlarged diameter, it will not be possible for this to go past said catch. At one side of tube 36 is also provided a plunger 76, actu-

ated by spring 77, tending to move the same forward in a longitudinal direction. Said plunger 76 is provided with a spring 78, projecting in the inside of tube 36 and allowing the forward motion of the cartridges 70 but preventing their return motion, the action of said spring 78 being substantially similar to that of springs 56, illustrated in Fig. 4.

When hammer 26 is in its cocked position, 75 as shown in Fig. 2, plunger 76 is forced backward against the action of spring 77. The operation of the device can now be easily understood as follows:

When breech block 24 is operated backward by the action of the recoil, the same pushes backward hammer 26; as soon as the empty shell has been ejected, catch 73 is allowed to move outward, thus permitting the motion of the cartridges within tube 36; 85 plunger 76 which is still free to move, hammer 26 still being on its way to its cocked position, actuated by spring 77 will then push the two cartridges which are in front of spring 78, forward, the first cartridge entering the firing chamber. As soon as the rear part of said first cartridge has cleared catch 73, and as the backward motion of breech block 24 progresses, said catch 73, is again forced down, thus preventing the motion of the remaining cartridges beyond its projecting end. In the meantime, rack 35 has been moved forward, pulling forward part 43 against the action of spring 62; as soon as the first cartridge in tube 36 is allowed to enter the firing chamber, said spring 62 will pull rod 41 and therefore ejector 38 forward, thus causing all the cartridges engaged by projections 39 to progress one step forward.

The forward motion of part 43 has caused the downward motion of connection 66 so as to clear and loosen the cam slot 53 previously engaged by pin 67. Slot 44 has a horizontal portion 79 and ejector 38 has four projections 80, two on each side. The sides or guides 37 between which said ejector 38 has moved, are each provided with two projecting surfaces 81.

When the breech block has ended its backward stroke thereby cocking hammer 26, the spring within part 30 which has been compressed by the same will begin to act, returning breech block 24 to its former position ready for firing. Through rack 33 and pinion 34, rack 35 is therefore moved backward, causing the backward motion of part 43 and of the ejector 38 connected to the same. The rear edge of projections 39 is inclined so that the same abutting against the cartridges in the storage chamber, which are prevented from getting back by springs 56, will lift ejector 38 until the backward motion of part 43 continuing, projections 80 will rest on projections 81, and the back- 130

ward motion of ejector 38 will be made in a raised position in which projections 39 are entirely clear of rotating magazine 48, and therefore allow the rotation of the same.

- 5 When ejector 38 is still in its raised position, the inclined part of slot 44 begins to act on pin 72, lifting connection 66 and therefore lever 64, connected to the same; the action of pin 67 against the left side of the new cam slot 53 now engaged, will cause the rotation of magazine 48. When this movement has started, projections 80 can clear projections 81, projections 39 resting on the surface of the magazine. As the backward motion of part 43 continues, slot 44 continues to lift connection 66 until the one step motion of the magazine is complete and ejector 38 is free to fall through the slot 55 of the new storage chamber registering with outlet 20 tube 57. The gun is now again ready for firing, and as the new shot is fired, the cycle of operations just described is repeated.

It is thus seen that as each shot is fired, all the cartridges contained in the storage 25 chamber, are moved one step forward, the first cartridge in tube 36 being pushed into the firing chamber; the magazine is then rotated and the cartridges in the next storage chamber will then be moved one step forward 30 and so on until the magazine has been emptied of all cartridges. It is obvious that the rotatory motion of the magazine can be obtained in many ways through the application of different mechanical means within 35 the reach of an ordinary mechanic; the device shown and described being intended mostly for a certain example.

To load the magazine, the rear part of the same 47, is provided with an opening 40 with which all the storage chambers register in succession as the magazine is rotated, said opening is closed by a plug 82 attached to a lever 83, pivoted in 84 to the rear part 47, and this can be moved away from the opening 45 for loading the magazine. When one storage chamber has been loaded through said opening, the step motion of the magazine can be caused by hand by pushing rod 29 and therefore breech block, 24 backward, 50 thus causing the entire cycle of movement to take place.

The sprocket portion 51 of part 50 is engaged by a pawl 85 pivoted in 86 to wall 45 and preventing the return motion of said 55 part 50 and therefore of the rotating magazine.

To facilitate the dropping of ejector 38 into the slot 55 of the storage chamber underneath, a spring 87 is provided pressing down rod 41.

From the foregoing it can be seen that I provide a device simple in construction and positive in its operation easily assembled and taken apart; one of the advantages of 65 my improved rotating magazine is that all

the space available is used for the cartridges, no space being given to springs or to other devices for controlling the motion of the same. It is obvious that the form and construction of the different parts need not be exactly as shown in the drawings, provided their relative functions remain the same; and while it is seen in the drawings that ejector 38 operates through the outside wall of the rotating magazine, it is clear that the mere 75 changing of said ejector to some other position, would not constitute a departure from the spirit of my invention.

Various other changes can be made in the specific details of construction of my machine without departing from my fundamental idea and I reserve to myself the right to bring to the same all those changes and modifications which should be suggested by manufacturing considerations and which 85 may enter fairly into the scope of the appended claims.

I claim:

1. In a device of the class described, and in combination with a firing mechanism, a 90 firing chamber, a longitudinal cartridge storage chamber, a cartridge feeding member, a recoil operated member, an element controlled by said recoil operated member, and an elastic connection between said element and said feeding member.

2. In a device of the class described, the combination of a firing mechanism, a firing chamber, a rotatable magazine comprising a plurality of longitudinal cartridge storage 100 chambers, means for imparting a step by step rotation to said magazine, a cartridge feeding member operating through one of the said chambers and moving all the cartridges within the same one step forward 105 during its forward movement, and means for moving said feeding member outward so as to clear said magazine after the forward motion of said cartridge has been accomplished; for the purposes as set forth.

3. In a device of the class described, the combination of a firing mechanism, a firing chamber, a rotatable magazine comprising a plurality of longitudinal cartridge storage chambers, means for imparting a step by 115 step rotation to said magazine, a cartridge feeding member operating through one of the said chambers and moving all the cartridges within the same one step forward during its forward movement, means for controlling the motion of said cartridge feeding member, and means for moving the same outward so as to clear the magazine during its return movement; for the purpose as set forth.

4. In a device of the class described, the combination of a firing mechanism, firing chamber, a rotary magazine comprising a plurality of longitudinal cartridge storage chambers, a cartridge feeding member, a re- 130

coil operative member, a step by step rotating mechanism for said magazine, means controlled by said recoil operative member, operating said step by step rotating mechanism, and elastic connections between said recoil controlled means and said feeding member.

5. In a device of the class described the combination of a firing mechanism, a firing chamber, a rotatable magazine comprising a plurality of longitudinal cartridge storage chambers, a step by step rotating mechanism for the same, an outlet tube for said magazine leading to said firing chamber, a rack-shaped feeding member, a recoil operated breech block, an element controlling the operation of said step by step mechanism, means for transmitting motion from said breech block to said element, and an elastic connection between said element and said feeding member.

6. In a device of the class described, the combination of a longitudinal cartridge storage chamber, a firing chamber, a tube leading from said storage chamber to said firing chamber, means for feeding cartridges to said tube, a breech block, a hammer, a catch engaging the outer cartridge within said tube preventing its forward motion, means for disengaging said catch as soon as an empty shell has been expelled from said firing chamber during the backward motion of said breech block, means exerting a pressure on said cartridge to feed the same to said firing chamber, means for subsequently returning said catch to its position of engagement with the next cartridge, and means for returning said breech block to its former position.

40. 7. In a device of the class described, the combination of a firing chamber, a cartridge feed tube leading thereto, a longitudinal cartridge storage chamber, a breech block, a hammer, a feeding member operated by said breech block, a catch normally retaining the cartridges within said tube against forward motion, and freeing the same when an empty shell is discharged from said firing chamber during the backward motion of said breech block, and yielding means exerting a pressure against said cartridges tending to force them toward said firing chamber.

8. In a device of the class described, the combination of a firing chamber, a breech block, a hammer, a longitudinal cartridge storage chamber, a tube leading from the same to said firing chamber, a member feeding the cartridges from said storage chamber to said tube, a longitudinally movable element controlled by said breech block, means transmitting the motion of said breech block to said element, in a reverse direction, an elastic connection between said element and said feeding member, a catch normally retaining the cartridges within said tube

against forward motion, and freeing the same when an empty shell is discharged from said firing chamber during the backward motion of said breech block, and yielding means exerting a pressure against said cartridges tending to force them toward said firing chamber.

9. In a device of the class described, the combination of a firing chamber, a recoil operated breech block, a hammer, a longitudinal cartridge storage chamber, a member feeding the cartridges from said storage chamber to said tube, a longitudinally movable element controlled by said breech block, means transmitting the motion of said breech block, to said element and said feeding member, a catch normally retaining the cartridges within said tube against forward motion, and freeing the same when an empty shell is discharged from said firing chamber during the backward motion of said breech block, yielding means exerting a pressure against said cartridges tending to force the same toward said firing chamber, and means for returning said breech block to its normal position.

10. In a device of the class described, the combination of a firing mechanism, a breech block, a rotatable cartridge magazine, a part integral therewith provided with cam-acting notches or indentations along its periphery, a cam-acting radially movable member engaging said notches or indentations causing a step by step rotation of said magazine, and means controlled by said breech block for operating the same.

11. In a device of the class described, the combination of a firing mechanism, a breech block, a rotatable cartridge magazine comprising a plurality of longitudinal cartridge storage chambers each adapted to contain a number of cartridges in an end to end succession, a longitudinally movable feeding member, a part integral with said magazine provided with notches or indentations along a circumference, a member movable in relation to the same for successively engaging with said notches or indentations to produce a step by step rotation of said magazine, a longitudinally movable cam acting element controlling the motion of the same, an elastic connection between said element and said feeding member, and means for transmitting motion from said breech block to said element; for the purposes as set forth.

12. In a device of the class described, the combination of a firing mechanism, a recoil operated breech block, a rotatable cartridge magazine comprising a plurality of longitudinal cartridge storage chambers each adapted to contain a number of cartridges in an end to end succession, a longitudinally movable feeding member, a part integral with said magazine provided with notches or indentations along a circumference,

member movable in relation to the same successively engaging with said notches or indentations to produce a step by step rotation of said magazine, a longitudinally movable 5 cam-acting element controlling the motion of the same, an elastic connection between said element and said feeding member, means for transmitting motion from said breech block to said element in a reverse direction, 10 and means for returning said breech block to its normal position; for the purposes as set forth.

13. In a device of the class described, the combination of a firing mechanism, a firing 15 chamber, a breech block, a rotatable magazine comprising a plurality of longitudinal cartridge chambers, an outlet tube leading the cartridges from said chambers to said firing chamber, a longitudinally movable 20 feeding member, means within said storage chamber preventing the backward motion of the cartridges therein contained, a catch engaging the outer cartridge within said tube preventing its forward motion, means for 25 disengaging said catch as soon as an empty shell has been discharged from said firing chamber during the backward motion of said breech block, means exerting a pressure on said cartridge to feed the same to said 30 firing chamber, means for subsequently returning said catch to its position of engagement with the next cartridge, a step by step mechanism for imparting a partial rotation to said magazine as each shot is fired, a longitudinally movable element controlling 35 said step by step mechanism, an elastic connection between said element and said feeding member, and means for transmitting motion from said breech block to said element; 40 for the purpose as set forth.

14. In a device of the class described, the combination of a firing mechanism, a firing chamber, a recoil operated breech block, a rotatable magazine comprising a plurality 45 of longitudinal cartridge storage chambers each adapted to contain a number of cartridges in an end to end succession, an outlet tube preventing the backward motion of the cartridges therein contained, a hammer, 50 a catch normally retaining the cartridges within said tube against forward motion, and freeing the same when an empty shell is discharged from said firing chamber, during the backward motion of said breech block, 55 yielding means exerting a pressure against said cartridges tending to force them toward said firing chamber, a longitudinally movable reciprocating rack-shaped feeding member operating within the storage cham-

ber registering with said outlet tube and pushing forward through one step all the cartridges therein contained during its forward motion, said feeding member clearing said magazine during its return motion, a step by step mechanism imparting a partial 60 rotation to said magazine as each shot is fired, and during the return motion of said feeding member, a longitudinally movable element controlling said step by step mechanism, an elastic connection between said element and said feeding member, means for transmitting motion from said breech block to said element in a reverse direction, and means for returning said breech block to its 70 normal position.

15. In a device of the class described, the combination of a firing mechanism, a firing chamber, a recoil operated breech block, a rotatable magazine comprising a plurality of longitudinal cartridge storage chambers, 80 each adapted to contain a number of cartridges from said chambers to said firing chamber, means within said chambers and outlet tube preventing the backward motion of the cartridges therein contained, a hammer, 85 a catch normally retaining the cartridges within said tube against forward motion, and freeing the same when an empty shell is discharged from said firing chamber during the backward motion of said breech block, yielding means exerting a pressure against said cartridges tending to force them toward said firing chamber, a longitudinally movable reciprocating rack-shaped feeding member operating within the storage chamber 90 registering with said outlet tube and pushing forward through one step all the cartridges therein contained during its forward motion, a part integral with said magazine provided with notches or indentations arranged along a circumference, a member movable in relation thereto successively engaging with said notches or indentations to produce a step by step rotation of said magazine, a longitudinally movable cam-acting element controlling the motion of the same, an elastic connection between said element and said feeding member, means for transmitting motion from 100 said breech block to said cam-acting element 105 in a reverse direction, and means for returning said breech block to its normal position; substantially as described, and for the purposes as set forth.

CARLO DE-FELICE.
